(57) **CLAIM**

The ornamental design for a wood stove, as shown and described.

DESCRIPTION

FIG. 1 is a top perspective view of a wood stove, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a partial enlargement of FIG. 2.

The dot-dash broken lines in FIGS. 2 and 9 represent boundaries of the enlarged portions and form no part of the claimed design.

The broken lines in the drawings illustrate the portions of the wood stove, which form no part of the claimed design.
